UNITED STATES PATENT OFFICE.

JAMES Z. TUCKER AND LOUIS W. MARKWORT, OF ST. LOUIS, MISSOURI.

SPARK-PLUG.

1,178,975.

Specification of Letters Patent. Patented Apr. 11, 1916.

Application filed April 16, 1914. Serial No. 832,232.

To all whom it may concern:

Be it known that we, JAMES Z. TUCKER and LOUIS W. MARKWORT, citizens of the United States, residing in the city of St. Louis and State of Missouri, have invented 5 certain new and useful Improvements in Spark-Plugs; and we do declare the following to be a full, clear, and exact description of the invention, such as will enable others skilled in the art to which it appertains to 10 make and use the same.

This invention relates to new and useful improvements in spark plugs and the primary object of the invention is to provide 15 a plug from which may be derived a plurality of sparks, which enable all of the gas sucked into the cylinders to be utilized, thus developing maximum power for the engine.

A further object of the invention resides 20 in providing a plug, the use of which will not be accompanied by the depositing of carbon on the plug, thus preventing any short circuiting in the use thereof.

Still another object of the invention resides 25 in providing an improved intermediate electrode between the main electrode and ground electrode which separates the sparks so as to provide substantially a double explosion in the use of this plug.

30 A still further object resides in providing a plug which is simple and durable in construction, inexpensive to manufacture, and one which will be very efficient in use.

With these and other objects in view our 35 invention consists in the novel features of construction, combination and arrangement of parts as will be hereinafter referred to and more particularly pointed out in the specification and claim.

40 In the accompanying drawing forming a part of this application:—Figure 1 is a side elevation of our device. Fig. 2 is a vertical section therethrough, and, Fig. 3 is a bottom plan view of the device.

45 In describing the invention we shall refer to the drawing in which similar reference characters designate corresponding parts throughout the several views and in 1 indicates a substantially cylindrical body 50 formed preferably of porcelain or other similar material having non-conducting qualities, said body being enlarged at a point adjacent its lower end as indicated at 2. This body is adapted to be received in 55 a shell or the like 3, the latter being provided with an internal annular shoulder 4

which receives thereagainst the enlarged portion 2 of said body, thereby limiting the movement of the latter with respect to the shell. The body is held in position in the shell 3 by means of a bushing nut 5 the latter being threaded into engagement with an internally threaded portion 6 formed at the upper portion of said shell 3. The body 1 is thus securely held in place in the shell 3 65 and the latter has a depending lower portion 7 formed thereon which is externally threaded and adapted for engagement with the threaded opening of a cylinder.

It must here be stated that the enlarged 70 portion 2 on the body has its upper face beveled downwardly and the lower peripheral edge of the nut 5 is correspondingly beveled to contact snugly therewith when said nut is turned home. The under face 75 of the enlarged portion 2 is likewise beveled upwardly and the extreme outer portion of this last mentioned beveled portion is flattened to provide a narrow annular shoulder 2' which rests directly on the annular shoulder 4 of the shell 3. Through the medium 80 of this construction, the lower portion of the body continuing from the enlarged portion 2 thereof is of the same diameter as the upper portion thereof and smaller than the 85 inner diameter of the depending annular portion 7, thus providing an annular space or chamber around the lower portion of said body. The plane of the lower peripheral edge of this depending portion 7 of 90 the shell 3 is below the plane of the lower portion of the body 1 and extending longitudinally through said body is a main electrode 8 the lower portion of which projects to a point below the plane of the lower peripheral edge of said portion 7. Mounted 95 in the lower peripheral edge of said portion 7 and projecting to the same plane as the lower end of the electrode 8 is a ground electrode 9. Also mounted in the body 1, 100 the same being substantially molded therein, is what may be termed an intermediate electrode 10, the latter projecting also to the same plane with the lower ends of the electrodes 8 and 9 and the lower end of said 105 electrode 10 is designed with a T-head as indicated at 10'. The ends of this T-head terminate at points in close proximity to the lower ends of the electrodes 8 and 9, thus providing spark gaps between the electrodes 8, 9 and 10. 110

The lower end of the body 1 at the points

from which the electrodes 8 and 10 project is provided with recesses or sockets 11 which are provided for the purpose of preventing soot and carbon from forming on 5 the electrode and other portions of the plug. It must here also be stated that the lower projecting portion of the body 1 is spaced from the lower projecting portion 7 of the shell 3 thus providing an annular space or 10 clearance therebetween. This clearance is also provided to prevent carbon and soot forming on the parts of the plug. Thus short circuiting will be eliminated, in the use of this device.

15 The main electrode 8 projects a short distance above the upper end of the body 1 of the plug and is threaded the same being engaged by the usual terminal nut 12 whereby a wire may be readily connected there- 20 with.

In the use of the device, it will be seen that two sparks will be formed through the medium of the three electrodes which sparks are formed simultaneously and if the mixture in the cylinder is a good one, a double explosion will take place. If the mixture is a poor one, however, this double sparking mechanism will make the explosion positive and thus this plug will be effective at all 25 times, regardless of the carbureting conditions. At the time of an explosion, the gas which enters the space or clearance between the shell and the body and which also enters the sockets or recesses 11 in the body, will be ignited and forced out of the cylinder, thus carrying therewith all carbon and soot 30 deposits. The plug is therefore cleaned of all deposits and is in condition for perfect ignition.

40 From the foregoing it will be seen that we have provided a simple, inexpensive and efficient means for carrying out the objects of the invention, and while we have particularly described the elements best adapted to 45 perform the functions set forth, it is obvious that various changes in form, proportion and in the minor details of construction

may be resorted to, within the scope of the appended claim, without departing from the spirit or sacrificing any of the principles 50 of the invention.

Having thus described the invention, what we claim is:

A spark plug of the class described, comprising a substantially cylindrical body 55 formed of non-conducting material and having a pair of sockets spaced at diametrically opposite points adjacent the center of the lower end thereof, the inner walls of said sockets being concaved, an annular enlargement formed on the body adjacent the lower end thereof, a shell receiving said body therein and having its lower peripheral edge in a plane below the plane of the lower end of said body, the lower portion of said 60 body being spaced from the inner wall of the shell, means for retaining said body in the shell, a main electrode projecting from the center of the upper end of the body and extending downwardly through said body 70 obliquely and projecting through one of the recesses in the lower end thereof, the lower terminal of said electrode being in a plane below the lower end of said shell, a ground electrode mounted on the lower end of said 75 shell, and an intermediate electrode mounted in the lower portion of said body and projecting through the other recess therein, the lower terminal of said electrode having a T-head formed thereon approximately 80 more than half the length of the radius of the lower end of said body and extending diametrically across the same from a point adjacent the main electrode in one recess across the other recess to a point adjacent 85 to the ground electrode.

In testimony whereof we have hereunto set our hands in presence of two subscribing witnesses

JAMES Z. TUCKER.
LOUIS W. MARKWORT.
